UNITED STATES PATENT OFFICE.

LOUIS PILLION, OF DIJON, FRANCE.

ELECTRIC CLOCK.

Application filed August 26, 1920. Serial No. 406,224.

To all whom it may concern:

Be it known that I, LOUIS PILLION, a citizen of the French Republic, residing at Dijon, Cote d'Or, France, have invented 5 certain new and useful Improvements in and relating to Electric Clocks, of which the following is a specification.

The object of the present invention is a secondary electric clock comprising at least 10 one series of rotary prisms on the lateral faces of which the hours are indicated.

Each of the prisms is preferably provided 15 with a driving mechanism placed under the control of a central member operated by the main clock to which the secondary clock is connected. The said central member will be in most cases a commutator which will insert periodically an electromagnet belonging to the mechanism of each of the prisms 20 on a local circuit of the secondary clock. Generally, the prisms are triangular and have transparent surfaces which allow a luminous source to be placed inside the prisms.

The accompanying drawings illustrate by 25 way of example only one mode of construction of a secondary electric clock according to the present invention.

Figure 1 is a front view of a clock according to the present invention showing 30 three series of prisms indicating the hours, the quarters of an hour, the halves of an hour and the minutes.

Figure 2 is a side view of a driving mechanism for each of the prisms.

Figure 3 is a side view of the same mechanism 35 90° from that of Figure 2.

Figure 4 shows a diagrammatic general arrangement of the indications on the faces of the prisms shown in Figure 1.

Figure 5 is a partial view of the commutator.

Referring to the various Figures, *a* are prisms each of which is rotatably mounted 40 on a shackle *b* screwed on to the wall of the clock; a small electric lamp *c* is placed inside the prisms. The prisms are integral with an axle *d* carrying a pinion *d'* the movement of which depends on that of a toothed wheel *e* integral with a ratchet wheel *f*. *e* and *f* are mounted on an axis *g* which carries also the anchor *h* of an electromagnet *i* the turns of which are connected to a commutator *k* comprising sixty main bars and a certain number of intermediate

bars, both kinds of bars being capable of 55 being successively inserted in the circuit of a primary cell by means of a brush *l*. The latter is rendered integral with a ratchet wheel having 60 teeth, and which is rotated through one-sixtieth of a revolution 60 by means of a locking mechanism (not shown) operated by an electromagnet each time that the said electromagnet is excited, that is, each time that the main clock sends an impulse into the circuit and connects it 65 to the secondary clock which we are describing. In this particular case the said impulses succeed each other every minute and each time the brush of the commutator will move from one main bar to another; it will insert in 70 the local circuit one or other or sometimes several electromagnets of the driving mechanism simultaneously. The excitation of the electromagnets will cause the anchor *h* to oscillate, the amplitude of the oscillation 75 being adjusted by means of stop pieces so as to be of 30°. The motion of the anchor is transmitted through its pawl to the ratchet wheel *f* which carries over the wheel *e* through a corresponding angle, the movement of the wheel *e* being transmitted to 80 the pinion *d'*. The ratio of the gears *e* and *d'* is as 4 to 1, so that the pinion *d'* will rotate through 120° at each oscillation, carrying the prism on the axle of which it is 85 mounted with it.

In the diagrammatic arrangement shown in Figure 2, the clock shows 0. In order that it shall show one o'clock the prisms *F* and *H* should be rotated through one-third 90 of a revolution each; the windings of their electromagnets will therefore be connected parallel to the corresponding bar of the commutator. In order that it shall show two o'clock it is again the prism *H* that 95 should be rotated through one-third of a revolution, the numeral II will be then in front; for three o'clock the prism *H* remains in the same position, the prism *J* rotates through one-third of a revolution adding 100 thus the numeral I to the numeral shown by the prism *H*; for four o'clock it is again the prism *J* that rotates; when it is rotated through another third of a revolution its numeral II will be added to the numeral 105 shown by the prism *H*; for five o'clock it is necessary to operate the prisms *G*, *H*, *J* by rotating each of them through one-third

of a revolution thus bringing the prisms H and J in their blank position and enabling numeral V of the prism G to be seen.

- For the quarters of an hour, halves and 5 three-quarters which are added to the number of minutes which are shown (the hour in Figure 1 is read 19^h 38^m) the working of the apparatus will be exactly the same. The 10 electromagnets of the prisms which are simultaneously displaced will be interconnected in parallel from the corresponding commutator.

The supplementary bars which have been mentioned above are provided in the case 15 when, for instance, the prisms of the upper part of the clock showing fourteen hours, that is, their faces which can be seen following each other in the following order:

- For the prism F, blank,
20 For the prism G, X,
For the prism H, II,
For the prism J, II,

it is desired to make the clock show fifteen o'clock. It is then necessary to rotate the 25 prism F through one-third of a revolution, the prism G through two-thirds of a revolution

to bring it at V and the prisms H and J through one-third of a revolution to bring them both at the fresh position.

The supplementary bar m is connected to 30 the electromagnet of the prism G in such a manner that the latter is excited twice when the brush of the commutator passes from one main bar to another main bar.

By this means it is obtained that it shall 35 rotate through 240°.

What I claim is:—

A secondary electric clock in which the dial comprises at least one series of prisms 40 on the faces of which the hours, the quarters of an hour and the minutes are indicated, in combination with a driving mechanism for each prism, a central member which operates the said driving mechanisms and means for operating the central member 45 from a main clock as set forth.

In testimony whereof I have signed my name to this specification.

LOUIS PILLION.
